CARBON HOLDER

Evan R. Evans, Elmira, N. Y., assignor, by mesne assignments, to American Sales Book Company, Inc., a corporation of Delaware

Application July 28, 1932, Serial No. 625,328

11 Claims. (Cl. 129—36)

This invention relates to improvements in manifolding devices such as manifolding books and in respect to its more specific features, it relates to a manifolding book embodying an improved device for holding transfer material.

One of the objects of the invention is to provide, in books of the class mentioned, an improved supporting and clamping device designed to support one or more carbon or transfer sheets in position for interleavement with record sheets of the book and being simple in structure, effective in operation and economical in manufacturing costs.

A further object is to provide for books of the class mentioned an improved clamping device for the transfer sheets designed to maintain the latter in smooth, operative position, to provide for quick and easy insertion or removal of the transfer sheets, and to provide a protective structure for the transfer sheets and record sheets and parts of the manifolding book disposed inwardly from the clamping device.

Other objects will be in part obvious and will, in part, be pointed out hereinafter.

For a further understanding of the invention, reference may be had to the accompanying drawing, in which

Fig. 1 is a perspective view of a manifolding book embodying the invention.

Fig. 2 is a detailed view of the carbon sheet holding device.

Fig. 3 is a cross section of the carbon sheet holder with the carbon sheet in position ready for use, and

Fig. 4 is a sectional view similar to Fig. 3 but showing the clamping bar in open position.

In the accompanying drawing a cover 1 includes a lower cover member 2 and an upper cover member 3, and a hinge or connecting portion 4. Mounted on the member 3 near the hinge 4 is a pair of spring pressed clamping jaws. The latter may be composed of upper and lower jaws 5 and 6 hinged together at 7. The lower jaw 6 is attached to the member 3 with suitable fasteners. Pressure is exerted on the jaw 5 by means of a spring so that its edge 8 normally presses against the corresponding edge of the jaw 6. It is preferable that the edges 8 be of saw tooth construction. A portion of the jaw 5 is turned up to form the handle 9 which may be used in opening the jaws.

A pad 10 of any desired construction may then be inserted between the jaws. Upon releasing the pressure on the member 9 the pad is firmly gripped between the jaws 5 and 6 and it will lie firmly and flatly against the member 3. Because of the

saw tooth construction of the edges 8, the pad cannot be displaced or removed from the cover without opening the clamping jaws.

While the construction disclosed in the above description and in the accompanying drawing is a preferred type of book, it is to be understood that the present invention may be used in conjunction with any type of manifolding book.

Affixed to the side of the member 3 is a carbon holder. This is more specifically shown in Fig. 2. The carbon holder may be composed of two metal plates 11 and 12. Suitable fasteners extend through the plates 11 and 12 into the cover member 3 thereby securing the carbon holder to the book. The members 11 and 12 have upwardly turned edges forming the flanges 13 and 14 and the latter are spaced apart to form a narrow groove 15. The flanged portions are preferably composed of a resilient material. Each flange may include two or more plies formed by bending the material backwardly upon itself to form the upper edges 16 and 17 as shown in Fig. 3. This structure serves to increase the strength of the flanges without materially detracting from their yielding and resilient properties, while at the same time smooth, rounded edges are presented functioning to avoid tearing or otherwise damaging the paper. It is preferred that the height of the outer flange 13 be equal to or greater than the thickness of the pad to be used in association therewith. It is likewise preferred that the height of the inner flange 14 be about one-half that of the pad.

Pivoted at 18 between the ends of the flanges 13 and 14 is the clamping bar 19. The latter is preferably slightly longer than the flange members and when in horizontal position extends through the groove 15. It likewise is made of a resilient material and may be a two-ply construction formed by bending the member upon itself. The plies may be spaced slightly apart, thereby making each side independently resilient as is shown at 19a in Fig. 4. In this construction, when the bar 19 is forced in place between the flanges 13 and 14, there is a compression of the members 19a with the corresponding tendency to hold the bar in place between the flange members. The clamping bar 19 may taper at its free end and terminate in a small knob-like handle 20. However, any type of handle may be employed.

A U shaped member 21 is preferably fitted over flange 14 at the end where bar 19 is pivoted. This is formed by folding a strip of metal upon itself so that one end engages one side of flange 14 and the other end engages the other side. It

is preferred that the member 21 be about equal in height to the top edge of the clamping bar 19. The pivot 18 extends through the flange 13, the clamping bar 19, the member 21 and the flange 14. The member 21 in this manner serves to give a firmer support to the arm 19 than would be offered by the comparatively low flange 14.

It is desirable that the clamping bar be held firmly and free from movement when it is in operating position, i. e. lying in a horizontal position in the groove 15 between the flanges 13 and 14. To accomplish this, a circular indent 22 may be stamped into the arm 19. To cooperate with this, a circular impress may be stamped into flange 13. This causes a circular protrusion 23 on the inner face of the flange which will engage the indent 22. To insure engagement of these elements the top of the inner flange 14 at the point opposite protrusion 23 may be inclined towards the flange 13 thereby pressing bar 19 against flange 13. At various points along the bar 19, detents or similar protrusions 24 may be formed to aid in holding the bar against accidental movement when in operating position.

In the preferred embodiment, the arm 19 is formed with a scallop like indentation at 25 by tapering the arm sharply from the pivoted portion to 25 and tapering it gradually from 26 to 25. In other words the edge of the clamping bar is cut away at an abrupt inclination to the bar edge to form the side of the indentation toward the pivotal mounting, while the cut at the other side of the indentation remote from the pivotal mounting is inclined gradually or less abruptly than the other side thereof.

It will be seen now that a manifolding pad of any desired type may be inserted between the clamping jaws. The clamping bar 19 is then raised to vertical position and a sheet of transfer material is placed face downwardly so that its one edge rests on the top 16 of the flange 13. The bar 19 is then lowered to horizontal position. The scalloped indentation 25 in arm 13 prevents wrinkling or puckering of the carbon paper, while the arm is being lowered. When the arm 19 is in horizontal position, the indent 22 cooperates with circular protrusion 23 and the carbon paper is locked firmly in position. As shown in Figure 3, the carbon paper may extend between the side of flange 13 and the side of bar 19, under bar 19, between the side of flange 14 and bar 19, over the top edge 17 of flange 14, and extends thence across the lower cover member. Due to the resilient nature of the flanges and bar, the carbon paper is held firmly in position, but is in no way torn or injured. The carbon sheet may then be placed between the leaves of the pad as desired and the book is ready for use. Of course, it is to be understood that more than one carbon paper may be employed in this manner depending upon the number of copies desired.

As above pointed out, the indentation 25 is formed in the lower strip-engaging edge of the clamping bar 19 near to the pivotal mounting thereof and its edge adjacent to the pivot is abrupt while the inclination of the opposite edge is relatively gradual. It should be noted, furthermore, that the edge of the indentation is positioned for direct cooperation with the upper edges of the clamping flanges 13 and 14 when the bar is swung toward its closed position to clamp the carbon sheets. As the bar swings from its fully opened position, as shown in Fig. 2, toward closed or clamping position, the gradually inclined forward edge of the indentation will

first contact with the near or adjacent edge of the carbon sheet. Due to the formation of the indentation as described, the bar will have swung well along toward its closed position before the carbon sheet is initially contacted by the gradually inclined edge of the indentation. Because of this relation of the parts, the angle between the sheet-engaging bar edge and the edges of the clamping flanges will be very small, and therefore the tendency of the 10 closing bar to crumple or to force the sheet outwardly away from the pivot will be practically nil. Therefore, by virtue of this indentation the clamping bar is moved into sheet-clamping position without any appreciable tendency to force 15 the sheet outwardly along the flange away from the pivot point, damage to the sheet being thus avoided and correct positioning thereof assured when it is secured in operative position.

It will be observed that the edge 17 of the flange 14 only extends to about the middle of the pad 10. The carbon paper, therefore, only has to be long enough to reach from this point to the far side of the top or the bottom of the pad. Furthermore the lower inner flange 14 provides for 25 more freedom of manipulation in interleaving the carbon sheet in position between the record leaves, whether the record book is of full thickness or whether it has been depleted by partial usage of the leaves. Also it will be observed that 30 the outer flange 13, being relatively wide and substantially equal in width to the thickness of a complete record book, and positioned at the edge of the cover member 3 along the edge of the book and outside of the carbon sheet, provides a 35 shield and protection for the inwardly disposed parts in addition to its sheet-clamping function.

It is apparent that the carbon sheet may be removed, reversed or replaced at will. If one portion should become unduly worn because of concentration of use, the sheet may be reversed thereby bringing a fresh portion into the area of concentrated use.

The manifolding book may be of the type that has original and duplicate leaves alternated 45 throughout the book. Of course, it is to be understood that the book may have an original and as many copy leaves as desired. The carbon sheet is inserted between the original and duplicate leaves. If there is more than one copy leaf, 50 the number of carbon sheets will accordingly have to be increased and will be inserted between the original and the first copy leaf and between each adjacent pair of the other copy leaves. It will be seen when the operator writes upon the 55 original that an accurate copy will be made upon the duplicate. When the entry upon a given leaf is complete, it is removed from the pad. As the pad is used and the leaves are removed, it will become thinner. It is for this purpose that the 60 inner flange member 14 preferably extends in height only to the center of the book. The carbon sheet will then have to extend only from this point to the top or the bottom at most. In this manner any overhanging of the carbon paper on 65 the far side of the pad is avoided.

Thus, by the above described construction are accomplished, among others, the objects hereinbefore referred to.

As many changes could be made in the above 70 construction and many apparently widely different embodiments of this invention could be made without departing from the scope thereof, it is intended that all matter contained in the above description or shown in the accompanying draw- 75

ing shall be interpreted as illustrative and not in a limiting sense.

Having described my invention, what I claim as new and desire to secure by Letters Patent is:

5 1. A clamping device including two perpendicular flanges formed of resilient material, said flanges being spaced laterally with respect to one another, a common base to which both of said flanges are secured, and a pivoted clamping bar positioned between said flanges, said clamping bar having two independently resilient sides.

10 2. A clamping device for sheet material including two parallel flanges formed of resilient material, said flanges being spaced laterally with respect to one another, a common base to which both of said flanges are secured, and a clamping bar having two independently resilient sides and a supporting pivot mounting it for engagement between said flanges, the lower face of said clamping bar being indented near said supporting pivot.

15 3. A clamping device for sheet material including two parallel flanges formed of resilient material, said flanges being spaced laterally with respect to one another, a common base to which both of said flanges are secured, a clamping bar having two independently resilient sides and a supporting pivot mounting it for engagement between said flanges, the lower face of said clamping bar being indented near said supporting pivot and means associated with said clamping bar and flanges to releasably lock the free end of the clamping bar between said flanges.

20 4. A clamping device for clamping sheet material, including, in combination, two parallel flanges formed of resilient material and attached in laterally spaced position relatively to each other, a clamping bar having a material engaging edge, and a pivotal support mounting said bar for movements away from said flanges and into position therebetween so as to clamp the sheet material between the sides of the bar and flanges, and said pivoted clamping bar having an indentation in its said edge near said pivotal support, said indentation opening through the edge of the clamping bar whereby the bar within said indentation engages the sheet material when the bar moves on its pivot into closed position so as to avoid abnormal puckering or displacement of the sheet material during initial pivotal closing movement of the clamping bar.

25 5. A clamping device for clamping sheet material, including, in combination, two parallel flanges formed of resilient material and attached in laterally spaced position relatively to each other, a clamping bar having a material engaging edge, and a pivotal support mounting said bar for movements away from said flanges and into position therebetween so as to clamp the sheet material between the sides of the bar and flanges, said pivoted clamping bar having an indentation in its said edge near said pivotal support, said indentation opening through the edge of the clamping bar whereby the bar within the indentation engages the sheet material when the bar moves on its pivot into closed position so as to avoid abnormal displacement of the sheet material during initial pivotal closing movement of the clamping bar, the edge of one of said flanges in alignment with the strip engaging part of said indentation of the clamping bar being straight.

30 6. In a clamping device for clamping sheet material in combination, two parallel flanges formed of resilient material and attached in laterally spaced position relatively to each other, a support

35 on one edge of which said flanges are mounted in upstanding position, a clamping bar, a pivotal support mounting said bar for movements away from said flanges and into position therebetween so as to clamp the sheet material between the sides of the bar and flanges, the inner of said flanges with reference to said support, having its upper edge terminating below the upper edge of the outer flange so as to provide for free positioning of the clamped sheet member inwardly of the 40 clamping device.

45 7. In a clamping device for clamping sheet material, in combination, two parallel flanges formed of resilient material and attached in laterally spaced position relatively to each other, a support on one edge of which said flanges are mounted in upstanding position, a clamping bar, a pivotal support mounting said bar for movements away from said flanges and into position therebetween so as to clamp the sheet material 50 between the sides of the bar and flanges, the inner of said flanges with reference to said support, having its upper edge terminating below the upper edge of the outer flange so as to provide for free positioning of the clamped sheet member 55 inwardly of the clamping device and said pivoted clamping bar having an indentation in its lower edge near said pivotal support and adjacent to the flange edge, so as to avoid puckering of the sheet material during initial closing movements 60 of the clamping bar.

65 8. In a clamping device for clamping sheet material, in combination, two parallel flanges formed of resilient material and attached in laterally spaced position relatively to each other, a support on one edge of which said flanges are mounted in upstanding position, a clamping bar, a pivotal support mounting said bar for movements away from said flanges and into position therebetween so as to clamp the sheet material 70 between the sides of the bar and flanges, the inner of said flanges with reference to said support, having its upper edge terminating below the upper edge of the outer flange so as to provide for free positioning of the clamped sheet member 75 inwardly of the clamping device, and the outer flange being wider than the inner flange and extending along one edge of the support and upwardly beyond the clamped sheet edge, and other inwardly disposed parts so as to provide a 80 protection therefor and for the edge of the support.

85 9. A carbon sheet holding device including two parallel flanges of resilient material, said flanges being spaced laterally with respect to one another, a common base to which both of said flanges are secured, a clamping bar having two independently resilient sides pivoted adjacent one end for movement between said flanges, said clamping bar being formed with a cut-away portion 90 adjacent to its pivot point for avoiding wrinkling or other damage to a transfer sheet when inserted into said holding device, and means for releasably locking the free end of said clamping bar between said flanges.

100 10. A clamping device for clamping sheet material, including, in combination, two parallel flanges formed of resilient material and attached in laterally spaced position relatively to each other, a clamping bar having a material engaging edge, and a pivotal support mounting said bar for movements away from said flanges and into position therebetween so as to clamp the sheet material between the sides of the bar and flanges, and said pivoted clamping bar having an inden- 105

5 tation in its said edge near said pivotal support, said indentation opening through the edge of the clamping bar whereby the bar within said indentation engages the sheet material when the bar moves on its pivot into closed position so as to avoid abnormal puckering or displacement of the sheet material during initial pivotal closing movement of the clamping bar, said indentation at its 10 end portion toward the pivotal support inclining abruptly to the bar edge, and inclining less abruptly at its strip engaging end portion disposed away from the pivotal support.

11. A clamping device for clamping sheet material, including, in combination, two parallel 15 flanges formed of resilient material and attached in laterally spaced position relatively to each other, a clamping bar having a material engaging edge, and a pivotal support mounting said bar for movements away from said flanges and into posi-

tion therebetween so as to clamp the sheet material between the sides of the bar and flanges, said pivoted clamping bar having an indentation in its said edge near said pivotal support, said indentation opening through the edge of the clamping bar whereby the bar within the indentation engages the sheet material when the bar moves on its pivot into closed position so as to avoid abnormal displacement of the sheet material during initial pivotal closing movement of the clamping 1 bar, the edge of one of said flanges in alignment with the strip engaging part of said indentation of the clamping bar being straight, said indentation at its end portion toward the pivotal support inclining abruptly to the bar edge, and inclining less abruptly at its strip engaging end portion disposed away from the pivotal support.

EVAN R. EVANS.
